UNITED STATES PATENT OFFICE.

REGINA KAHN, OF MILWAUKEE, WISCONSIN.

GAS-IGNITER.

1,207,926.

Specification of Letters Patent. Patented Dec. 12, 1916.

Application filed September 23, 1912. Serial No. 721,762.

To all whom it may concern:

Be it known that I, REGINA KAHN, a citizen of the United States, residing at Milwaukee, county of Milwaukee, and State of Wisconsin, have invented new and useful Improvements in Gas-Igniters, of which the following is a specification.

My invention relates to improvements in that class of gas igniters, which are adapted 10 to be centrally located between a plurality of gas burners and from which radial jets of gas automatically ignited by a pilot light are caused to flash out in close proximity to said burners, whereby gas may be simultaneously ignited in all or any one of said 15 burners at the pleasure of the operator.

My invention pertains more especially among other things, 1st, to the peculiar construction of the igniter, and 2nd, to the construction and relative arrangement of the gas controlling valve by which gas is admitted to such igniter.

My invention is further explained by reference to the accompanying drawings, in 25 which—

Figure 1 represents a plan view of the igniter centrally located between several gas burners of the ordinary construction. Fig. 2 is a vertical section of the igniter, the gas 30 controlling valve and a side view, partly in section, of the duct leading from the valve to the igniter, and Fig. 3 is a horizontal section, drawn on line x—x of Fig. 2.

Like parts are identified by the same reference numerals throughout the several views.

1 represents the top of a gas stove of ordinary construction.

2 is a gas burner. The several burners 2 are connected with the main gas supply pipe 40 3 by the several branch ducts 4, each of which is provided with an ordinary gas controlling valve 5.

6 represents the igniter. The igniter comprises two reversely curved disks 7 and 8 45 which together form a chamber, both of which are supported from the vertical tube 9. The lower disk 7 is provided with a central aperture 10 and is supported from the sides of the tube 9, near its lower end, while the disk 8 is preferably provided with a screw threaded aperture 11, which has threaded bearings 12 on the top of the tube 9, whereby it is adapted to be adjusted upwardly and downwardly nearer to or farther from the opposing disk 7. The inversely curved disks 7 and 8 are adjusted at

a slight distance apart leaving an annular space 13 for the free admission of air and for the escape of the jets of flame 14 by which the gas which in escaping from the igniter 6 is ignited.

15 is a lock nut, by which the disk 8 is secured at any desired point of adjustment nearer to or farther from the disk 7.

The lower disk 7 is provided with a plurality of apertures 16 for the admission of air, which is adapted to enter the space between the disks 7 and 8 in a vertical course at right angles to the jets of gas or flame 14, whereby the air and gas are more thoroughly commingled together. The vertical tube 9 is provided with a plurality of radial ports or apertures 17 for the escape of gas.

18 is a small pilot duct for supplying the pilot light 19 with gas, whereby as soon as 75 gas is admitted to the vertical duct 9, it is ignited, when the radial flame 14 is projected outwardly, whereby the gas which is escaping from any one or more of the burners 2 is instantly ignited. The igniter 6, comprising the several parts described, is connected with the main gas duct 3 through the duct 20, valve chamber 29 and supporting L 21. The gas is admitted to the pilot light 19 from the main duct 3 through the branch ducts 22 and 23 and the small pilot duct 18, and the amount of gas admitted to the duct 18 is regulated by the screw 23', which has threaded bearings in the outer end of said branch duct 23.

The admission of gas to the duct 20 and thence to the igniter proper is controlled by the spherical ball valve 25, and said valve 25 is adapted to be forced to its seat 26 by the spiral spring 27, said spiral spring being interposed between said spherical ball valve 25 and the reducing sleeve 28, which reducing sleeve has threaded bearings in the walls of the valve chamber 29. The valve 25 is adapted to be instantaneously thrown back 95 from its seat by a forward pressure upon the push button 30, which push button is connected with the valve 25 through the valve stem 31. The valve stem 31 has slideable bearings in the valve chamber 29.

32 is a packing nut of ordinary construction by which the escape of gas around the valve stem 31 is prevented.

The burners 2 are provided with a plurality of apertures 33 for the escape of gas.

It will now be understood that when any one or more of the gas controlling valves 5

leading to the burners 2 have been opened, the gas thereby admitted to such burners will be instantaneously ignited by a quick forward push upon the push button 30. By pushing 5 forward upon the push button 30, gas will be instantaneously admitted to the space between the disks 7 and 8, when it will be ignited by the pilot flame 19, whereby the jets of burning gas or flame 14 will flash out in 10 the four directions, as indicated in Figs. 1 and 3, whereby the gas which has previously been admitted to any one or more of the burners 2 will, as stated, be instantaneously ignited. It will also be understood that the 15 disks 7 and 8 may be adjusted nearer to or farther from each other, whereby the length of the radial jets 14 may be increased or diminished to correspond with the distance of the burners 2 from such igniter, and that 20 the disk 8 may be rigidly locked at any desired point of adjustment by turning down the lock nut 12 upon the upper side of said disk. It will also be understood that when the radial jets of flame 14 flash outwardly 25 from between the disks 7 and 8, the currents of air induced by said jets are caused to rush inwardly between said disks, as indicated by the arrows 34 shown in Fig. 3, whereby a greater volume of air will be consumed and the volume of gas otherwise required to produce said jets will be proportionately reduced.

Having thus described my invention, what 30 I claim as new, and desire to secure by Letters Patent, is—

1. The combination with a main gas sup-

ply duct of a branch duct and a vertical duct provided with a plurality of radial ports, means for controlling the admission of gas to said vertical duct and ports, a pair of disks respectively supported from said vertical duct upon the respective sides of said ports, a pilot duct communicating from said main gas supply duct and having its discharge end terminating between said disks, 40 means for controlling the admission of gas to said pilot duct, one or more gas burners connected with said main gas supply duct, and means for controlling the admission of gas to said burners. 45

2. The combination of a main gas supply duct and a vertical duct provided with a plurality of radial ports, means for controlling the admission of gas to said vertical duct and ports, a pair of disks respectively supported from said vertical duct upon the respective sides of said ports, means for adjusting said disks nearer to or farther from each other, a pilot duct communicating from said main gas supply duct and having its discharge 50 end terminating between said disks, means for controlling the admission of gas to said pilot duct, one or more gas burners connected with said main gas supply duct, and means for controlling the admission of gas 55 to said burners.

In testimony whereof I affix my signature in the presence of two witnesses.

REGINA KAHN.
